UNITED STATES PATENT OFFICE.

WILLIAM H. ROACH, OF FULTON STATION, KENTUCKY.

EVAPORATING-PAN.

SPECIFICATION forming part of Letters Patent No. 248,506, dated October 18, 1881.

Application filed August 16, 1881. (No model.)

To all whom it may concern:

Be it known that I, WILLIAM H. ROACH, of Fulton Station, in the county of Fulton and State of Kentucky, have invented a new and useful Improvement in Evaporating-Pans; and I do hereby declare that the following is a full, clear, and exact description of the same, reference being had to the accompanying drawings, forming part of this specification, in which—

10 Figure 1 is a plan view of my improved evaporating-pan. Fig. 2 is a vertical longitudinal section on line $x-x$, Fig. 1. Fig. 3 is a vertical longitudinal section on line $y-y$, Fig. 1; and Fig. 4 is a vertical transverse section on line $z-z$, Fig. 1.

15 My invention relates to improvements in pans for evaporating saccharine fluids; and it consists, first, in the peculiar construction and arrangement of gutters and a perforated plate, whereby the scum is automatically conducted out of the pan, thus making the pan, when in operation, a self-skimming one.

20 My invention further consists in certain details of construction hereinafter more fully set forth.

25 In the accompanying drawings, A represents my improved evaporating-pan, of any desired length, and adapted to be inserted in an arch over a fire.

30 a and b represent two parallel transverse partitions, extending across the pan near its rear end, and forming two compartments, $c d$, of the same width. The width of the compartments $c d$ depends upon the length of the pan A, and the width of these compartments is usually about one and three-sevenths inch for every foot in length of the evaporating-pan, although these dimensions may be varied as desired. The compartment c is provided with 35 an opening, e , in one end, near its bottom, for the passage of the saccharine fluid out of the pan, and an opening, f , is made in one end of the partition a , near its bottom, governed by a sliding gate or valve, g , whereby the flow of 40 the saccharine fluid into the compartment c can be regulated as desired.

45 h represents a baffle-plate, arranged in the compartment d , opposite the opening f and sliding gate g , to impart a more tortuous flow 50 to the saccharine fluid, as hereinafter described.

The partition b is provided with the openings

$i j$ near its bottom and at each end, which lead into the longitudinal compartments $k k'$, arranged on opposite sides of the pan. The compartments $k l m k'$ are formed by the parallel longitudinal partitions $n o p$, extending from the front end of the pan to the transverse partition b . q and r represent openings at the bottoms of the partitions n and p , near the front end of the pan, thus forming communications between the compartments k and l and m and k' . The partitions n and p are each provided with an offset or gutter, s , near its upper edge. These gutters s are slightly inclined from the front toward the rear of the pan, so as to convey the scum which rises to the surface of the boiling fluid toward the rear of the pan, and thence over the surface of a perforated plate, t , slightly inclined laterally, and connecting the inner ends of the gutters, and leading to an opening, u , in the side of the pan, whereby the scum is automatically conducted from the surface of the saccharine fluid out of the pan. In the passage of the scum over the perforated plate t , in its passage out of the pan, any saccharine fluid that may be carried with the scum will pass through the perforations in the plate and fall back into the compartments $l m$. By this construction the labor of skimming is avoided, the skimming process being automatic.

55 In practice the sirup or saccharine fluid is introduced into the compartments $l m$ at their inner ends, and passes, in the direction of the arrows, through the openings q and r , into the compartments $k k'$, thence through the openings $i j$ into the compartment d , and thence through the opening f , governed by the sliding gate g , into the compartment c , and thence through the opening e out of the pan, the saccharine fluid being thus forced to take a very circuitous route from its entrance into the pan until its departure therefrom.

60 I claim as my invention—

1. The combination, with the compartments $l m$, having partitions $n p$, provided with inclined gutters s , of a plate connecting the inner ends of the gutters, and adapted to automatically carry the scum through an opening in the side of the pan, substantially as described.

2. The combination, with the compartments

l m, having partitions *n p*, provided with inclined gutters *s*, of the perforated plate *t*, connecting the inner ends of the gutters, and adapted to automatically carry the scum through an opening in the sides of the pan, and allow the saccharine fluid in the scum to fall back into the pan, substantially as described.

3. The evaporating-pan herein described, consisting of the pan *A*, provided with the

parallel longitudinal compartments *k l m k'*, having openings *i j q r*, gutters *s*, perforated plate *t*, and transverse compartments *c d*, separated by the partition *a*, having opening *f* and sliding gate *g*, substantially as described, and 15 for the purpose set forth.

WILLIAM H. ROACH.
